(Cl. D42—8)

To all whom it may concern:

Be it known that I, Gerard B. Desouches, a citizen of the French Republic, residing at Paris, France, have invented a new, original and ornamental Design for a Combined Wrist Watch and Strap Therefor, of which the following is a specification, reference being had to the accompanying drawing, forming part thereof:

Fig. 1 is a fragmentary front view, slightly in perspective, of a combined wrist watch and strap therefor, showing my new design;

Fig. 2 is a fragmentary rear view; and

Fig. 3 is a side elevational view of my combined

wrist watch and strap therefor, with the essential features illustrated in full line.

I claim:

The ornamental design for a combined wrist watch and strap therefor, substantially as shown and described.

GERARD B. DESOUCHES.
